UNITED STATES PATENT OFFICE.

STANLEY GEORGE BELSCH, OF DETROIT, MICHIGAN.

DESIGN FOR A SIGN.

Application filed March 25, 1927. Serial No. 21,320. Term of patent 3½ years.

To all whom it may concern:

Be it known that I, STANLEY G. BELSCH, a citizen of the United States, residing at Detroit, in the county of Wayne and State of Michigan, have invented a new, original, and ornamental Design for a Sign, of which the following is a specification, reference being had to the accompanying drawing, forming part thereof.

Figure 2 is an edge elevation of my sign, showing my new design, the side ornamentation having been omitted for convenience.

I claim:

The ornamental design for a sign, as shown.

STANLEY GEORGE BELSCH.
